SIDE SLIPPING WEFT DETECTOR FOR
LOOMS

Albert Cederlund, Worcester, Mass., assignor to
Crompton & Knowles Loom Works, Worcester,
Mass., a corporation of Massachusetts

Application February 8, 1949, Serial No. 75,240

5 Claims. (Cl. 139—283)

1

This invention relates to improvements in side slipping weft detectors for looms and it is the general object of the invention to provide a detector wherein the detecting element or finger can be readily removed and replaced.

One type of side slipping weft detector employs a pivoted lever and a detector finger slidable thereon along an axis offset from the pivot of the lever in the direction of the length of the bobbin being detected. The detector finger is generally provided with some form of roughened surface which embeds itself in a sufficient supply of weft to prevent turning of the lever but slides on a bare bobbin to effect rocking of the lever when the weft is depleted. The detector finger is normally held in rearward detecting position by some form of light spring which is compressed when ample weft is present but resists compression when weft is absent and causes the lever to swing.

These detector fingers are subject to damage because of their light-weight delicate construction and it is occasionally necessary to replace them. Furthermore, the character of weft being woven may change from time to time, in which event it is desirable to use a feeler tip most appropriate to the type of weft in use. It is an important object of the present invention to provide a weft detector so constructed as to permit easy replacement of a detector finger. The detector includes a retaining cap removable from the lever and when in position providing with the lever a cavity or recess for reception of part of the detector finger and its spring.

It is usually necessary to hold the tip of the feeler with its corrugations or the like in vertical position and it is a further object of the invention to provide a member secured to the detector element having a flat surface to engage and slide along part of the retaining cap to resist turning of the detector element.

It is a more specific object of the invention to provide the lever with a pair of spaced lugs to position the retaining cap and provide one of the lugs with a laterally opening slot through which the detector finger can be moved after removal of the cap.

The aforesaid lever is normally held by a torsion spring in such position as to place the detector tip properly for engagement with the bobbin being detected. This spring has one end connected to the lever and another end adjustably connected to a collar or the like adjustable angularly on a stud on which the lever is pivoted. In the past it has been possible to set this collar

2

down so close to the lever as to resist free movement of the latter. It is a still further object of the invention to construct the stud with a stop which will prevent the collar from engaging the lever.

With these and other objects in view which will appear as the description proceeds, the invention resides in the combination and arrangement of parts hereinafter described and set forth.

10 In the accompanying drawings, wherein a convenient embodiment of the invention is set forth.

Fig. 1 is a side elevation of part of the weft replenishing mechanism having the invention applied thereto, the shuttle box and lay being shown in cross section.

Fig. 2 is an enlarged plan view looking in the direction of arrow 2, Fig. 1,

Fig. 3 is an enlarged vertical section on line 3—3, Fig. 2,

20 Fig. 4 is a horizontal section on line 4—4, Fig. 3, and

Fig. 5 is a detailed vertical section on line 5—5, Fig. 4.

Referring particularly to Fig. 1, the loom frame 25 supports a magazine foot 11 on which is mounted a stud 12 for the transerrer arm 13. The stud has secured thereto an arm 14 to which a support 15 is secured in adjusted position by a bolt 16. A stud 17 extending horizontally through the support 15 has mounted on the forward end thereof a carrier 18 upturned at its forward end 19 for engagement with a lateral projection 20 of the transerrer arm at the time of a weft replenishing operation. A spring 21 interposed between the carrier 18 and stationary support 15 normally holds a carrier 18 in rear position. The rear end of the carrier is provided with two bolts 25 extending vertically through the carrier and also through a flat preferably sheet metal base 26 of the weft detector which is designated herein generally as D.

The matter thus far described is of common construction and of itself forms no part of the present invention. The mounting for the base is that used on rayon looms, but any other convenient form of mounting for plate 26 can be employed.

Referring more particularly to Figs. 2 and 3, the base 26 has secured thereto an upright stud 27 having an upper reduced end 28 to define a shoulder 29. A lever 30 has a hub 31 rotatable on the lower part of the stud 27 and surrounded by a torsion spring 32 the lower end of which is operatively connected to the lever as at 33 and the upper end 34 of which is inserted into one of

several holes 35 in a collar 36. The latter rests on the shoulder 29 and is thus kept spaced from and out of engagement with the lever 30, and is held in fixed angularly adjusted position on stud 27 by a set screw 37.

The lever 30 has a flat laterally extending arm 40 which is enlarged as at 41 and formed with front and back lugs 42 and 43, respectively, which project as viewed in Fig. 4 to the right of a substantially straight vertical wall 44 on the lever, the wall extending back and forth and being transverse of the bobbin being detected, preferably at right angles to the bobbin when the lever 30 is in normal position. The front lug is provided with a preferably round hole 45 extending horizontally in a back and forth direction, while the rear lug 43 is formed with a slot 46 which opens laterally, or in a direction away from the main part of lever 40, as shown in Fig. 5.

A retaining cap 50 is formed with flat parallel top and bottom plates 51 and 52, respectively, joined by a vertical wall 53 which engages the lugs 42 and 43 and is positioned by them. The right hand parts of the top and bottom plates 51 and 52, the wall 53, and the wall 44 on the lever provide an inclosed pocket or recess designated herein at 55. A small bolt 56 passing through the top and bottom plates and also through the lever 40 holds the cap to the lever. This bolt may have a head 57 engaging top plate 51 and have a nut 58 screwed on the bottom thereof. When the nut and bolt are removed the cap can be slipped off lever 40.

The detector finger designated generally at 60 comprises a straight wire 61 to the rear end of which is secured a feeler tip 62 having vertical corrugations represented at 63 in Fig. 2. The wire 61 extends through the slot 46 and the cavity 55 and has its forward end extending through hole 45 in lug 42. A lightweight compression spring 65 surrounds that part of the wire 61 in the recess 55 and has its forward end in engagement with lug 42 and has its rear end in engagement with a shoulder or stop 66 which is fastened to the wire 61, as by welding or soldering. The spring 65 normally holds this shoulder against the rear lug 43. The stop may be of square form as shown more particularly in Fig. 3 so that its top and bottom and right side as viewed in Fig. 3 will be close to or engage the adjacent parts of cap 50, while the left side thereof as seen in Fig. 3 is close to or engages wall 44 of lever 30.

In operation, the torsion spring will hold the lever 30 normally in the position shown in Fig. 2. At each detecting beat of the loom a bobbin B will be presented to and engage the tip 62. If sufficient weft for continued weaving is present the teeth or corrugations 63 will become embedded in the weft and the wire 61 will be moved forwardly against the action of light compression spring 65. When insufficient weft is present, as indicated in Fig. 2, the detector tip will move to the right from the position shown in Fig. 2 without substantial compression of the spring 65. This will effect rocking of lever 30, and this rocking can be utilized to give indication of weft exhaustion. As shown herein the indication is given electrically.

Lever 40 has a forward extension 70 to which is secured a depending pin 71 for engagement with a plunger 72 of an electric switch 73 secured to the under side of the base 26, as by screw 74. The switch will normally be open when the parts are in the position shown in Fig. 2, but when the detector lever 40 swings in a clockwise direction

as viewed in Fig. 2 upon engagement of the tip 62 with a depleted bobbin the pin 71 will move to the left, thereby freeing the plunger 72 and permitting closure of the switch. The wires 75 and 76 which are thus electrically connected within the switch may lead to any approved form of loom controlling circuit.

When it is desired to remove or replace the detector wire 61 the bolt 56 will be removed and the cap 50 slipped off the lever. This will remove the wall 53 from restraining position with respect to the wire 61 and the stop 66, and the wire 61 can be moved from the full to the dotted line position shown in Fig. 4, after which the wire can be moved rearwardly to remove its forward end from the hole 45. After a new detector element 60 has had its forward end inserted into the hole 45 and is slipped back to the full line position shown in Fig. 4 the cap can be replaced. During this exchange of detector elements the part of the wire 61 immediately to the rear of the stop 66 will slide in the open slot 46.

From the foregoing it will be seen that the invention sets forth a simple form of side slipping weft detector wherein the detector elements can be readily removed and replaced by taking the retaining cap off the lever 30 and then moving the detector element laterally away from the lever and then rearwardly. The stop 66 is of such form that it prevents the wire 61 from turning on its axis and therefore maintains the tip 62 in correct position. While all four sides of this stop have been shown as flat and capable of engagement with adjacent surfaces either on the retaining cap or the lever 30, it will of course suffice if only one face of the stop is flat and in engagement with one or another of the flat surfaces on either the cap or lever. It will also be seen that the shoulder 29 limits downward movement of the collar 36 and prevents the latter from frictionally interfering with the relationship of the forces exerted by springs 32 and 65 when the detector indicates.

Having thus described the invention it will be seen that changes and modifications of the foregoing specific disclosure may be made without departing from the spirit and scope of the invention.

What is claimed as new is:

1. In a side slipping weft detector for the weft bobbin of a loom, a base normally at rest, pivot means on said base, a flat detector lever mounted on said pivot means for angular movement, resilient means normally holding the lever in detecting position, spaced front and back lugs on said lever projecting laterally therefrom, a retaining cap having top and bottom plates held on said lever and having a side wall engaging and positioned by said lugs, said retaining cap and lever defining a recess between said lugs, a detector finger slidably mounted through said lugs and recess and having a feeler tip secured to the rear end thereof, and a spring surrounding the detector finger within the recess engaging the forward lug and acting on the finger urging the latter rearwardly.

2. In a side slipping weft detector for the weft bobbin of a loom, a base normally in stationary position, a lever pivotally mounted on the base and having spaced front and rear lugs and a wall extending between said lugs, a retaining cap removably mounted on the lever and having top and bottom plates and having a connecting side wall engaging and positioned by the lugs, the wall of the lever and said retaining cap defining a recess

between said lugs, a detector finger having a feeler tip secured to the rear end thereof, said finger extending through the recess and having a shoulder adjacent to the rear lug, and a spring surrounding that part of the detector finger located within the recess engaging the front lug and holding the shoulder yieldingly against the rear lug, said rear lug having an open slot therein through which the detector finger extends, said slot being normally closed by said retaining cap, the latter when removed from the lever permitting removal of the detector finger through said slot.

3. In a side slipping weft detector for the bobbin of a loom, a base normally in stationary position, a flat lever pivotally mounted on the base and extending laterally from the axis of the lever in the direction of the length of the bobbin, front and rear spaced lugs on said lever, the lever having a wall between said lugs located intermediate the latter and the axis of the lever, a retaining cap having flat top and bottom plates and a side wall positioned by said lugs and spaced from the wall of the lever, removable means holding the retaining cap on the lever so that said wall of the lever and the retaining cap normally define a recess between said lugs, the rear lug having a slot therein opening in the direction away from said axis of the lever and normally closed by said side wall of the retaining cap, a detector finger extending through said slot and recess and front lug and having a shoulder thereon within the recess for engagement with the rear lug, said finger having a feeler tip secured to the rear end thereof, and a spring surrounding that part of the detector finger within the recess engaging the front lug and normally holding the shoulder yieldingly against the rear lug, said retaining cap when removed permitting lateral removal of that part of the finger adjacent to said shoulder through said open slot.

4. In a side slipping weft detector for the weft bobbin of a loom, a base normally in stationary position, a detector lever pivotally mounted on the lever and having a part thereof extending laterally from the axis of the latter in the direction of the length of the bobbin, front and rear lugs on said lever extending from the latter in a direction away from said axis, the rear lug having a slot opening in a direction away from the stud and the front stud having a hole therein opening in a direction toward the rear lug, a detector finger extending through said slot and hole and rearwardly beyond the rear lug and having a feeler tip secured to the rear end thereof, a shoulder on the detector finger for engagement with the rear lug, a spring surrounding that part of the detector finger between the shoulder and the front lug normally holding the shoulder yield-

ingly against the rear lug, a retaining cap having a side wall positioned by said lugs normally closing said slot, removable means normally holding the retaining cap on the lever, said shoulder engaging said side wall of the retaining cap to limit movement of the finger in said open slot when the cap is in position on the lever, said cap when removed from the lever permitting lateral movement of the detector finger out of said slot.

5. In a side slipping weft detector for the weft bobbin of a loom, a base normally at rest, a detector lever, pivotal connections between the base and the lever, said lever extending laterally from said pivotal connection in the direction of the length of the bobbin and having a forwardly and backwardly extending wall, a front lug on the lever extending in the general direction away from said pivotal connection, a rear lug on the lever at the rear part of said wall extending generally in the direction away from said pivotal connections, the front wall having a hole therethrough and the rear lug having a slot opening in a direction away from said pivotal connection, a detector finger comprising a straight wire extending through the slot in the rear lug and the hole in the front lug and having a feeler tip secured to the rear end thereof, a spring surrounding the detector finger and engaging the front lug, a shoulder on said detector finger between said lugs engaged by the spring and normally held yieldingly against the rear lug, and a retaining cap removably held on said lever having a side wall engaged and positioned by said lugs and spaced by the latter from said wall on the lever and normally closing said open slot, said shoulder being positioned for engagement with said side wall of the retaining cap to limit movement of the detector finger in said slot in a direction away from the pivotal connection, and said shoulder and cap being formed to operate to prevent angular or axial movement of the finger relatively to said cap, said retaining cap when removed permitting the detector finger to be moved laterally out of the open slot and then rearwardly for removal from the hole in the front lug.
